UNITED STATES PATENT OFFICE.

GEORGE C. ANTHON, OF NEW YORK, N. Y., ASSIGNOR TO STANLEY INSULATING COMPANY, OF GREAT BARRINGTON, MASSACHUSETTS, A CORPORATION OF MAINE.

VACUUM BOTTLE.

Application filed March 5, 1921. Serial No. 449,673.

This invention relates to thermally insulated receptacles of the type generally known as vacuum bottles, and particularly to those in which the spaced shells of the receptacle are made of metal, such as steel, joined together at the neck of the bottle as by means of welding; and it constitutes an improvement in the device shown in the United States Patent to Stanley No. 1,071,198. In that patent a metal vacuum bottle is shown, in which the vacuous space contains a filler of finely divided insulating material, which affords in itself a barrier to conduction, convection and radiation and also serves as a mechanical spacing element between the shells. This filler has usually been silocell, (silocell being the trade name of kieselguhr or diatomaceous earth) though the use of charcoal has been attempted. It has been found that although a filler of charcoal was desirable because of the resulting thermal efficiency of the bottle, much difficulty was experienced in vacuumizing a space filled with finely divided charcoal, because it would be sucked out of the vacuous space in the operation of pumping. And accordingly it has heretofore been thought best to fill the vacuous space with such a material as silocell, which, when compacted to some extent, seems to maintain its compacted mass form and resist the suction of the pump.

It is an object of my invention to secure, so far as possible, the advantages flowing from the use of a filler such as charcoal, while eliminating the practical difficulty above referred to. I am able to accomplish this result by filling the vacuous space almost entirely with finely divided charcoal, partly compressed in the usual way, and interposing in the small remaining section of the vacuous space, between the main body of charcoal and the pumping orifice, a relatively small mass of such a material as silocell, which is less finely divided than the charcoal, and then vacuumizing the entire space. In this way the suction exerted at the pumping orifice is effective on the charcoal filler, through the silocell barrier and the escape of charcoal through the pumping orifice is prevented.

Other objects and aims of the invention, more or less broad than those stated above, together with the advantages inherent, will be in part obvious and in part specifically

referred to in the course of the following description of the elements, combinations, arrangements of parts, and applications of principles constituting the invention; and the scope of protection contemplated will appear from the claims.

In the accompanying drawings, which are to be taken as part of this specification, and in which I have shown merely a preferred form of embodiment of the invention,

Figure 1 is a diametrically vertical sectional view through part of a typical vacuum bottle illustrating the application of my invention;

Figure 2 is a collective view in similar section illustrating the parts, detached, which go to make up the lower end of the bottle shown in Figure 1;

Figure 3 is a top plan view of the baffle plate shown in section in Figure 2; and

Figure 4 is a top plan view of the inside or true bottom shown in section in Figure 2.

Referring to the numerals on the drawings, 5 indicates the inner shell and 6 the outer shell of a vacuum vessel having the general characteristics of that illustrated in the Stanley patent above mentioned, it being understood that these two shells are joined as by welding at the upper or neck portion of the bottle, the mouth of the inner shell being indicated at 4, and the weld joint being made adjacent the mouth. The vacuous space between the two shells is indicated at 7, and according to my invention I propose to fill this space from the closed or neck portion thereof at the upper end of the bottle down to a point very close to the lower end of the space and indicated, for instance, by the dotted line 8, with finely divided wood charcoal or equivalent material. The space from the line 8 down to a baffle 9 which defines the lower end of the vacuous space, is filled with finely divided silocell or equivalent material. It will be understood that the charcoal and the silocell are put into the space 7 while the bottle is upended and they may be suitably compressed as they are put in. After the covering layer of silocell has been introduced the baffle 9, which may have the general form shown, with depending peripheral spring-flange 10, is slid up inside of the outer shell 6 to confine the filler mass within the vacuous space. As shown, this baffle 9 may be centrally dished and provided with aper-

110

tures 11. The dished portion is furthermore covered with a pad of steel wool 12, and this in turn overlaid with a piece of wire netting 14, of suitably fine mesh, the edges of 5 the netting being preferably spot-welded to the surface of the baffle. The baffle having been shoved up into position about as shown in Figure 1, the inner wall of the outside shell 6 is carefully cleaned below the 10 spring-flange 10, and then the inner or true bottom 15, which has a depending peripheral spring-flange 16 and is centrally dished, is shoved up into position until it contacts with the flange of the baffle 9. Thereupon, 15 the flange portion 16 of the true bottom 15 is welded to the inner wall of the outside shell 6. The dished portion of the true bottom 15 is provided with a pump-connection tube 17, through which suction is applied 20 to the vacuous space.

It has been found that with a construction such as described, if the filler of the vacuous space were composed of finely divided charcoal, a considerable proportion of the 25 same would be drawn out to the pump, escaping through the apertures 11 and between the spring-flange 10 and the inner wall of the shell 6. However, by making that part of the filler body which directly 30 overlies the baffle 9 of such a material as silocell, not so finely divided as the charcoal, and somewhat compacted, I find that there is substantially no loss of the filler material due to the action of the pump, and 35 that after the pumping operation the bottle shows a distinctly better thermal efficiency, whether this be due to the use of a charcoal filler throughout the greater part of the vacuum space, or to the fact that a more 40 effective pumping is possible.

The use of the barrier 9 is important, because it enables me to hold the filler in position so that the entire surface of the shell 6 may be cleaned, as is necessary in preparing 45 for the welding into position of the true bottom 15. The spring flange 10 in itself accomplishes a wiping or cleaning action as it is shoved into position and holds the barrier while the inner wall of the shell 50 6 is additionally cleaned off. The screen 14 and the steel wool pad 12, and particularly the latter, are used to prevent the escape of the silocell during pumping. After the pumping operation the tube 17 is slid off in 55 the usual way and then a false bottom 18 is fitted over the end of the shell 6 and suitably secured to give the desired finish to the article.

It will be understood that I contemplate 60 no limitations as to the materials which may be employed, so long as they answer the

purposes which I have in mind. Thus, while I specify the use of finely divided wood charcoal as a filler for the major part of the vacuous space, and a less finely divided silocell as a filler and barrier pad between the charcoal and the baffle, I may use other materials having similar properties. For instance, in place of silocell I might conceivably use charcoal not quite so finely 70 divided as that which is used for the major part of the vacuum space.

Inasmuch as many changes could be made in the above construction, and many apparently widely different embodiments of 75 my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described 85 and all statements of the scope of the invention which, as a matter of language, might be said to fall therebetween.

I claim:—

1. A vessel having spaced walls defining 90 between them a space which is to be exhausted, the outer wall having an exhaust aperture therein, a mass of finely divided filler for the space immediately overlying the exhaust aperture, and a distinct mass of 95 more finely divided filler for the remainder of the space, and a pad of steel wool between the first named filler and the exhaust aperture, substantially as and for the purposes set forth.

2. In combination, an inner vessel having a mouth and a bottom, an outer tubular shell surrounding and spaced away from the inner vessel, joined to the inner vessel adjacent the mouth of and extending and open beyond the bottom of the latter, an apertured baffle plate within the open end of the outer shell and spaced away from the bottom of the inner vessel, a closure for the open end of the outer shell, provided with a pump connection, a pad having the characteristics of steel wool carried by the baffle plate over the aperture thereof, a filler immediately above the baffle plate having the characteristics of compacted silocell finely divided, and a filler having the characteristics of finely divided charcoal in the remainder of the space between the vessel and the outside shell, the last named filler being more finely divided than the first named filler.

In testimony whereof I affix my signature.
GEORGE C. ANTHON.
